UNITED STATES PATENT OFFICE

ALFRED JAMES JONES, OF BRISTOL, AND FREDERICK NICHOLAS, OF LAWRENCE WESTON, ENGLAND, ASSIGNEES TO E. S. & A. ROBINSON, LIMITED, OF BRISTOL, ENGLAND

SLITTING AND WINDING APPARATUS

Application filed June 28, 1928, Serial No. 288,898, and in Great Britain September 10, 1927.

This invention relates to improvements concerned with the cutting or slitting of paper webs and the re-reeling thereof, of the type wherein steel cutters or slitting discs are 5 adapted to co-operate with a hardened steel or like backing roller or cylinder.

While the invention may be applied generally to slitting or the subdivision of paper and the like, as for example paper delivered 10 by paper coating or printing machines or webs proceeding from paper-making machines and the like, it is particularly suitable for use as an adjunct or attachment to machines wherein a continuous web is subjected 15 in transit to a treatment such as a glazing or waxing process as known in the art concerned with the production of bread wrapping paper.

An object of the present invention is to 20 provide improvements whereby a tighter and more uniform roll or reel of paper or the like is obtained.

A further object of the invention lies in 25 providing means whereby difficulties of alignment in reeling or re-reeling are overcome or reduced.

It will be appreciated that where paper 30 (such as waxed paper) intended for use in connection with foodstuffs, is concerned, any means which avoid or minimize handling or exposure, conduce to hygienic conditions. Thus the present invention, as applied as an 35 adjunct to a waxed paper treating machine, possesses advantages in that intermediate re-reeling of the paper and consequent additional handling and exposures are avoided.

According to the invention as applied in association with the slitting or subdivision 40 of a web, a spindle or core (or an axially aligned plurality thereof) upon which the slit webs are to be wound, is directly driven (preferably through a friction clutch). A roller is employed adapted to engage the roll and web as it is wound and is adapted to 45 combine the dual functions of a pressure roller and a hardened backing for the slitting discs. The slitting discs are mounted in close proximity to the re-reeling point and are preferably mounted in contact with the back- 50 ing and pressure roller at a point less than

half the circumference of said roller from its point of contact with the reel. The slitting discs and pressure or backing roller are mounted upon a pivoted or displaceable frame adapted to be variably weighted or 55 arranged as a spring counterbalance so that the pressure upon the reel may be maintained uniform irrespective of the growth of the reels while permitting adjustment of pressure as may be necessary. 60

In the accompanying drawings:—

Figure 1 is a side elevation of the re-reeling and slitting device.

Figure 2 is a partial plan corresponding thereto.

Figure 3 is an end elevation showing the drive to the re-reeling spindle and constructional details of the latter.

In carrying the invention into effect according to one convenient mode, a re-reeling spindle or core 9 is mounted to rotate in bearings 14 carried by brackets fixed to a supporting structure such as 7. This spindle 9 is adapted to be driven from an appropriate transmission element through a strong friction clutch 10 (Figure 3) which is adapted to drive the re-reeling spindle continuously but allowing slip when the tension of such reeling affords a certain resistance. 70

Referring to Figure 3, which shows a preferable mounting for the re-reeling spindle 9, the drive to the clutch 10 may be through a belt or any other suitable gearing. The clutch drives the re-reeling spindle through the gears 12 and 13, the latter being permanently fixed to the spindle. The spindle may be readily removed from position by 80 opening the hinged cap bearings 14. 85

It is to be observed that the friction clutch is necessary or desirable where the splitting attachment is used in conjunction with any machine where the paper speed is constant. On the other hand, where the speed of the paper may increase as the rewound reel grows, the re-reeling spindle may be definitely driven, the friction clutch being unnecessary. 90

The spindle 9 is formed as a centre bar having a number of taper portions 15. Engaging the taper portions are wedges 16 100

fixed to the inner walls of a tube 17 that is divided longitudinally into, say, three parts. A nut 18 mounted upon a screwed part of the spindle 9 serves to cause relative longitudinal movement between the spindle and the three part tube, whereby the latter is expanded to grip strawboard spools 19 on which the paper web is rewound. The nut is provided with a recess 20 to receive one end of the three part tube, the other end being accommodated in a recessed collar 21 which is held in position by a spring 22 abutting against a collar 23 pinned to the spindle.

In order to take up end play of the spindle 9, according to one arrangement, an adjustable collar 24 having a grub screw 25 is provided and adapted to be adjusted along the spindle to abut against the bearing 14 whereby the spindle is definitely located for endwise movement by the collar and a second collar 26 disposed between the gear wheel 13 and the adjacent bearing. Ball thrust races may be provided between the collars 24 and 26 and the respective bearings.

In association with the re-reeling spindle 9 a frame 30 is provided which is adapted to carry a hard backing roller 31 (which is also intended to be employed as a pressure roller for the reels) and the slitting discs 32. This frame is pivotally mounted upon a transverse spindle or in trunnions 33 so that it may have a swinging movement relative to the reeling spindle 9. The pivot for the frame is preferably disposed in a plane below the axis of the re-reeling spindle and the frame is preferably extended away from the spindle position for the purpose of affording a counterweight lever, the arrangement being such that the addition of counterweights is adapted to cause the opposite end of the frame to bear towards the re-reeling spindle. At its forward end the frame carries the hardened steel roller 31 (or a plurality thereof) mounted in ball bearings so that such is (or are) free to rotate. This roller 31 is preferably disposed so that it lies more or less beneath the reel spindle 9 and is adapted to contact with the paper of the reels as such are formed. The frame 30 is also adapted to support the cutter or slitting discs 32 which may be mounted upon spindles 34 carried in bearings or located in slots 35 in pivoted arms 36 supported in slotted brackets 37 which in turn are rigidly connected to the cross shaft 38 carried in brackets 39 bolted to the frame 30. A pair of leaf or other spring members 40 is adapted to bear upon the arms 36 carrying the cutter spindle so that the cutters are constantly thrust into cutting contact with the hardened roller. Means may be provided such as a set screw 41, in connection with the leaf springs for adjust-

ing the pressure of said springs, the arrangement preferably being such that the pressure of the springs is applied to a point beyond the pivotal point of the brackets carried by the frame so that the spring pressure holds the cutter discs up to their work while they may be readily removed by turning the brackets about their pivot.

To facilitate the raising of the cutter discs 32 or the displacement thereof away from the backing roller 30, a handle 42 is rigidly connected to the cross shaft 38 and carries a pawl 43 adapted to engage in the notches 44, 45 in a quadrant 46 forming an extension of one of the brackets 39.

When the discs 32 are in the operative position the pawl 43 engages in the notch 44, but when in the inoperative position it engages in the notch 45.

In association with the pivoted counterbalanced frame 30 means may be provided in the form of pawls or catches 47 cooperating with a bar 48 on the frame so that when the frame is swung down to move the backing roller and cutting discs away from their operative position for removal of the re-reeled web, the frame may be temporarily held out of position by the catches.

The paper web 49 is passed under and around the backing and pressure roller 31 and then over the reeling spindle 9 in a direction counter to that in which it is passed around the pressure roller. The arrangement of the pivoted frame 30 and the cutter discs 32 is such that the cutter discs contact with the backing roller and slit the paper at a point in close proximity to the re-reeling point of contact where the hardened pressure roller bears against the reels. The distance of the slitting contact point from the pressure reel contact point should be less than the semicircular extent of the backing and pressure rollers and it may be very considerably less, for example it may be slightly under a quarter of a circle. The virtue of effecting the slitting operation in close proximity to the re-reeling point lies in the fact that this arrangement eliminates any difficulties which might otherwise be experienced in the maintenance of alignment in the re-reeling operation and avoids interlocking of the reels and the necessity of manipulation or adjustments with regard to the proper "tracking" of the web. It will be noted that with the arrangement shown, after the web is slit, the portions of the web remain in contact with the pressure roller until they are rewound.

The counterpoise of the frame, whether it be effected by the addition of weights or by the employment of a spring balance device, may be adjusted so that the correct pressure is brought to bear on the paper as it is rewound in order to afford the requisite tension to cause the reel tightly to be formed.

Moreover, it will be observed that by the arrangement described this pressure and tension is maintained substantially constant and does not vary as the reel grows in size. By 5 the adjustment of the clutch and weights or spring devices the tension of re-reeling may be varied to suit the weight or kind of paper being slit and reeled.

The slitter discs 32 are of known character 10 and together with their supporting brackets are mounted adjustably on the cross shaft 38 so that their lateral position may be spaced according to the desired subdivision of the parent web.

15 Having now described our invention, what we claim as new and desire to secure by Letters Patent is:—

1. Apparatus for slitting a web of paper or the like and re-reeling the divided web 20 comprising a re-reeling spindle, fixed bearings in which said spindle rotates, means for directly driving said spindle, a backing roller around which the web is passed, one or more disc slitting knives co-operating with 25 said backing roller and a counter-weighted displaceable frame carrying the backing roller and slitting knives, the arrangement being such that the backing roller is pressed against the growing rewound reel with a substantially constant pressure.

2. Apparatus as claimed in claim 1 and wherein the counterweighted displaceable frame is pivotally mounted and is adapted to be variably weighted for maintaining 35 pressure on the growing reel.

3. Apparatus for slitting a web of paper or the like and re-reeling the divided web comprising, a supporting structure, a re-reeling spindle, bearings for said spindle fixed 40 relatively to said supporting structure, means for directly driving said spindle, a backing roller around which the web is passed, a plurality of disc slitting knives co-operating with said backing roller, a counterweighted frame pivotally mounted in 45 bearings carried by said supporting structure, said frame carrying the backing roller and slitting knives and causing the backing roller to be pressed against the growing reel 50 wound reel with substantially constant pressure, and a catch pivotally mounted on said structure and adapted to engage a part of said frame temporarily to hold the backing roller away from the rewound reel for removal thereof.

In testimony whereof we have signed our names to this specification.

ALFRED JAMES JONES.
FREDERICK NICHOLAS.
